UNITED STATES PATENT OFFICE

130,255

DESIGN FOR A BRUSH

Albert Racicot, Aurora, Ill., assignor to National Brush Company, Aurora, Ill., a corporation of Illinois

Application June 21, 1941, Serial No. 101,607

Term of patent 3½ years

To all whom it may concern:

Be it known that I, Albert Racicot, a citizen of the United States, residing at Aurora, in the county of Kane and State of Illinois, have invented a new, original, and ornamental Design for a Brush, of which the following is a specificcation, reference being had to the accompanying drawing, forming part thereof, in which:

Figure 1 is a perspective view of the brush
showing my new design;

Figure 2 is a top plan view thereof; and Figure 3 is a side elevational view thereof.

The characteristic feature of my design resides in the brush of the specific configuration and proportions shown in the drawing.

I claim:

The ornamental design for a brush, substantially as shown and described.

ALBERT RACICOT.
